US00D892540S

(12) **United States Design Patent** (10) **Patent No.:** **US D892,540 S**
Collins et al. (45) **Date of Patent:** **** Aug. 11, 2020**

(54) **FOOD CONTAINER BASE**(71) Applicant: **Zume, Inc.**, Mountain View, CA (US)(72) Inventors: **Julia Collins**, San Francisco, CA (US);
Casper W. Chiang, Danville, CA (US);
Chester Wajda, San Francisco, CA (US)(73) Assignee: **Zume, Inc.**, Mountain View, CA (US)(***) Term: **15 Years**(21) Appl. No.: **29/698,689**(22) Filed: **Jul. 18, 2019****Related U.S. Application Data**

(62) Division of application No. 29/574,808, filed on Aug. 18, 2016, now Pat. No. Des. 861,422.

(51) **LOC (12) Cl.** ..... **07-99**(52) **U.S. Cl.**

CLAIM

The ornamental design for a food container base, as shown and described.

DESCRIPTION

FIG. 1 is a top isometric view of a food container base showing our new design.

FIG. 2 is a bottom isometric view thereof.

FIG. 3 is a top plan view thereof.

FIG. 4 is a bottom plan view thereof.

FIG. 5 is a front elevational view thereof.

FIG. 6 is a rear elevational view thereof.

FIG. 7 is a left side elevational view thereof; and,

FIG. 8 is a right side elevational view thereof.

Stippling in the drawings represent the three-dimensional contours of the design, and are not intended to indicate surface decoration.
